UNITED STATES PATENT OFFICE.

EDWIN NORTON, OF MAYWOOD, ILLINOIS, ASSIGNOR, BY MESNE ASSIGNMENTS, TO AMERICAN CAN COMPANY, OF JERSEY CITY, NEW JERSEY.

AUTOMATIC SHEET-METAL-ROLLING MILL.

SPECIFICATION forming part of Letters Patent No. 680,998, dated August 20, 1901.

Application filed March 10, 1899. Serial No. 703,555. (No model.)

To all whom it may concern:

Be it known that I, EDWIN NORTON, a citizen of the United States, residing in Maywood, in the county of Cook and State of Illinois, have invented a new and useful Improvement 5 in Automatic Sheet-Metal-Rolling Mills, of which the following is a specification.

My invention relates to improvements in sheet-metal-rolling mills.

- 10 In the manufacture of thin sheets of steel from bars the bars are ordinarily first rolled in single thicknesses until the heat is exhausted or the metal drawn to the proper length for the next step, which consists in rolling the 15 reduced bars or sheets in pairs or double thicknesses after being first returned to the furnace and reheated, and after being rolled in two thicknesses they are doubled or made into a pack of four thicknesses, reheated, and 20 rolled in such pack of four thicknesses, when they are again doubled or made into a pack of eight thicknesses, returned to the furnace and reheated, and finally rolled in such pack of eight thicknesses to the required gage. 25 Furnaces are commonly built along one side of the mill, next to the feeding-in side thereof, and in hand-operated mills the bars or sheets are passed back over the top of the rolls, which involves a great amount of manual labor and cost. In the automatic rolling-mill 30 invention of my former United States patent, No. 600,165, of March 8, 1898, the metal bars, plates, or packs of sheets are passed first in one direction and then in the opposite direction through and between a single stand of 35 rolls by means of automatically-actuated feed-tables and automatically-actuated feed-screws for setting down the rolls to produce the desired reduction at each pass or series of 40 passes and mechanism for automatically reversing the rolls and feed-tables until the bars, plates, or packs of sheets require re-heating, when they are again passed automatically back and forth between the rolls 45 until they have received the required reduction, thus effecting a material saving in time, labor, and power and materially increasing the capacity or output of the mill over that of the hand-operated mills previously in use. 50 The objects of my present invention are to further improve and perfect the automatic sheet-metal-rolling mill of my said former patent, to facilitate the operations performed by the mill and further increase its capacity or output, to greatly cheapen the cost of construction of a tin-plate works equipped with my automatic rolling-mills, to condense the plant into much less room than formerly required, saving thereby in buildings and in cost of 55 handling the materials or output of the mills during their operation, to effect a saving of labor in handling the bars, sheets, or packs during the heating and rolling operations, and to reduce the metal more quickly than heretofore, thus saving greatly in the power 60 required for the work.
- My invention consists in the means I employ to accomplish these objects or results—that is to say, it consists in combining in an automatic reversible rolling-mill two stands 70 of rolls arranged tandem or one in front of the other, each provided with its feed-table and connected by a conveyer between the two stands of rolls, with mechanism for controlling the action of the rolls in reducing the metal 75 and mechanism for reversing the two stands of rolls and driving both stands of rolls in unison first in one direction and then in the other and mechanism for automatically reversing the two feed-tables and the connecting-conveyer, by which arrangement and combination of parts the heated bars or packs of sheets are made to pass quickly through both stands of rolls before the initial heat is lost by the delay of stopping and reversing 80 the feed-tables and rolls. At each reversal of my improved mill the bars or packs of sheets thus receive four reductions or passes, and as four passes or reductions or a multiple thereof are usually made between heats the bars 85 or packs of sheets are thus left on the furnace or feeding-in side of the mill convenient to return to the furnace. My improved automatic mill, it will thus be observed, effects a material saving in labor over what would be 90 required if two automatic reversing mills of my said former patent were set separately, while the capacity or tonnage turned out is substantially equal to that of two of such separate mills and that a great saving is effected 95 in machinery and in cost of construction, a single reversing device answering for both 100

stands of rolls and the same power plant serving for both stands, as only one stand of rolls is acting upon the bars or sheets at a time, and that a great saving is also effected in the building, room, or space necessarily occupied.

My invention also consists in the combination, with the rolls and their feed-tables, of an automatic bar feeding or delivering and spacing device for feeding or delivering and spacing the series of bars, usually four in number, accurately, quickly, and properly to and upon the feed-tables, the feed-tables being provided with devices for automatically squaring and truing the bars thereon, so that they will properly enter the bite of the rolls for the first pass and at such uniform distances between the bars as to prevent all possibility of their overtaking or overlapping each other, and thus occasioning great waste of material and danger of breaking the rolls.

My invention further consists in the combination, with the rolls and their feed-tables and the automatic bar delivery or feeding devices for spacing the bars upon the bed of the feed-table for the first pass between the rolls, of auxiliary gaging and truing devices for squaring and truing the bars or sheets after the first pass, so that at each succeeding pass between the rolls the bars or sheets will be delivered central and true to the bite of the rolls.

It further consists in the combination of two or more stands of automatic reversing rolls, feed-tables adapted to deliver the bars or sheets properly to the bite of the rolls in each direction, and devices for gaging or squaring the metal bars or sheets upon the bed of the feed-tables between the passes, whereby the rolling of the bars or sheets is caused to proceed rapidly at each pass of the metal between the rolls.

It further consists in the combination, with two or more stands of reversing rolls, of feed-tables for conveying the heated bars or sheets to each of the stands of rolls in both directions and mechanism for automatically setting down or adjusting the feed-screws of each of the stands of rolls in co-operative relation one to the other to give the proper reduction to the metal at each pass of the bars or sheets between each stand of rolls.

It further consists in the combination, with two or more reversing stands of rolls, of a reversing mechanism adapted to take its power from a shaft revolving continuously in one direction and impart to each stand of rolls and their feed-tables an instantaneous reversal, the one reversing mechanism operating to drive both stands of rolls first in one direction and then in the other.

It further consists in two or more reversing stands of rolls with their feed-tables and feed devices adapted to work in unison, in combination with a reversing device and mechanism for driving the rolls and feed-tables first in one direction and then in the other.

It further consists in the novel construc-

tion of parts and devices and in the novel combinations of parts and devices herein shown and described, and specified in the 70 claims.

In the drawings forming a part of this specification, and in which similar characters of reference indicate like parts throughout all the views, Figure 1 is a plan view of an automatic double or tandem reversing sheet-metal-rolling mill embodying my invention. Fig. 2 is a side elevation of the same. Fig. 3 is an enlarged detail plan view. Fig. 4 is a detail central longitudinal vertical section. Fig. 5 is a detail end elevation, and Fig. 6 a detail plan view, of the reversing mechanism. Fig. 7 is a detail cross-sectional view showing the movable side gages of the roller feed-table. Fig. 8 is a detail plan view showing the mechanism for automatically operating said side gages. Fig. 9 is a detail view showing mechanism for operating the roller feed-tables. Fig. 10 is a detail longitudinal section showing the automatic devices for feeding, delivering, and spacing the bars upon the roller feed-table for the first pass. Fig. 11 is a cross-sectional view of the roller feed-table, showing in elevation the bar feed or delivering and spacing devices and the mechanism for operating the same. Fig. 12 is a detail sectional view, partly in elevation, showing the mechanism for automatically turning or adjusting the feed-screws for setting the rolls closer together after one pass for a succeeding pass. Figs. 13 and 14 are diagram views illustrating the feeding or adjusting of the two stands of rolls for the passage of the bars or sheets first in one direction and then in the other between the same.

In the drawings, *a* represents the frame of the machine or mill. The mill is provided with two stands of rolls *b b c c*, arranged tandem or one after another, with a sufficient distance between the two stands to give room for the series of bars, sheets, or packs of sheets, which are usually four in number, to extend one after another without danger of overlapping, as they are elongated by the rolling operation.

d e are the roller feed-tables on each side of the tandem-arranged stands of rolls, and *f* is the roller feed-table between the stands of rolls. The roller feed-table *d* at the feeding-in side of the double or combined mill and which feeds the series of bars, sheets, or packs of sheets into the first pair of rolls *b b* is provided with two bar feeding or delivering devices *g g*, each preferably consisting of a rocking or tilting box, each having slots or openings *h i* at their opposite sides for the bars to slip through, a pair of bars *x* being taken from the furnace and placed by the workmen in each box, the slots *h* being flush with the bottom of the box and the slots *i* being the thickness of the bar *x* above the bottom of the box, so that when the box is tilted to one side the upper bar will slip out automatically through the slot *i* on one side, while

the lower bar α will slip out through the slot h on the opposite side when the box is tilted in the opposite direction. The tilting boxes or delivering devices g thus deliver the bars 5 α on the roller feed-table with a space or interval between the series of bars. To aid in truing and squaring the bars on the roller feed-table and to space them a proper distance apart thereon, the roller feed-table is 10 provided with a series of vertically-movable gates or spacing-plates k , each adapted to be moved up between rolls of the roller feed-table, so that as the rolls move the bars forward they will strike against the stops, and 15 thus be arrested and held a proper distance apart until the gates k are simultaneously withdrawn. The roller feed-tables d e are further each provided with a pair of laterally-movable side gages l l , which by opening 20 and closing upon the series of bars, sheets, or packs of sheets on the roller feed-table serve to center and straighten the same on the feed-table, and thus cause them to enter and pass centrally and properly and truly between 25 the rolls. These gages l l are automatically operated, as may also be the gates or stops k k and the bar feeding or delivering devices g g at suitable intervals. The shafts m n of the lower rolls b c of each stand of rolls are 30 geared together by intermeshing gears o p q , so as to revolve in unison.

r is the driving-shaft, revolving continuously in one direction and from which the mill is driven first in one direction and then 35 in the opposite direction through the reversing device or mechanism.

The reversing device or mechanism, through which motion is communicated from the driving-shaft r to the roll-shafts m n first in one 40 direction and then in the opposite direction, preferably comprises a pair of gears s s , fixed to the driving-shaft r , a pair of loose gears t t on the clutch-shaft u , and a gear v on a counter-shaft w , the gear s meshing directly with 45 one of the loose gears on the clutch-shaft and the other gear s on the driving-shaft communicating motion in the opposite direction to the clutch-shaft u through the intermediate gear v , which meshes with the other gear t 50 on the clutch-shaft.

y is the friction-clutch, operated by the clutch-lever z and by which one or the other of the loose gears on the clutch-shaft is fixed thereto, and thus drives the mill first in one 55 direction and then in the opposite direction.

The feed-screws 2 2 , by which the rolls are set closer and closer together at intervals, as required, turn in screw-threaded housings 3 of the frame and bear at their lower ends 60 against the journals of the upper roll of each pair or stand of rolls. The feed-screws 2 2 are automatically turned at intervals, or at each reversal of the mill, by power communicated to them from the feed-screw driving-pulley 4 through suitable connecting mechanism or gearing including a clutch 5 , by which the feed-screw-driving shaft 7 is con-

nected at intervals to the driving-pulley 4 . The devices or mechanism for automatically operating the clutch 5 at each reversal of the motion of the mill consists of an oscillating cam 8 , secured frictionally to the shaft m of the lower roll b , and which is adapted to oscillate slightly to one side or the other until it engages one or the other of the stops 70 9 9 , attached to the frame. The frictional connection between the cam 8 and the shaft m permits the roll to continue its rotation after the cam engages the stop, while at the same time causing the clutch 5 to be operated 75 and turn the feed-screws to set the rolls for the next pass of the series of bars, sheets, or packs of sheets between the rolls, this being done at the beginning of the reversal of the motion of the mill. Motion is communicated 80 from the cam 8 to the movable member of the clutch 5 by a reciprocating slide 10 , having a pin or roller 11 , engaging the cam, and which is provided at its upper end with a pawl or dog 12 , which is adapted to engage 85 a collar 13 on the clutch-operating rod 14 . A spring 15 holds the pawl normally in position to engage said collar. A stationary cam 16 , engaging the free end of the pawl or dog 12 , causes it to disengage said collar on 90 the clutch-rod after having first operated the clutch-rod, so that the spring on the clutch-rod may return to position to again disengage the clutch after the feed-screw-driving shaft 95 7 has made one revolution.

The feed-screw-driving shaft 7 is provided with a gear 18 , engaging a gear 19 on a shaft 20 , said gears being preferably so related to each other that the shaft 20 makes, for example, one revolution to every five revolutions of the shaft 7 . The shaft 20 has a gear 21 , which meshes with a segment-gear 22 on the feed-screw shaft 2 . The feed-screw shafts 2 2 for each stand of rolls are geared together by intermeshing gears 23 23 24 . 105 The gears 23 23 instead of being fixed directly to the shafts of the feed-screws 2 2 are connected thereto through the medium of worm-gears 25 25 , which fit on the squared ends of the screw-shafts 2 2 and which 110 worm-gears engage worms 26 , journaled in brackets on said gears 23 23 , so that by turning the worms 26 by hand the screws 2 2 may each be independently turned or adjusted in respect to each other, as may be 115 required from time to time to compensate for wear or to bring the rolls truly parallel to each other. The feed-screws of the two pairs or stands of rolls are geared together, so that one pair of feed-screws is operated from 120 the other by bevel-gears 27 28 29 30 , the gears 28 and 30 being on a connecting-shaft 31 and the gear 28 being larger than the gear 30 , so that the feed-screws of the first pair of 125 rolls will be turned or set down a greater amount than those of the second pair as the bars pass twice between the second pair of rolls before they return again to the first pair of rolls. This will be readily understood from 130

the diagram views, Figs. 13 and 14, in which Fig. 13 represents the position in which the first pair of rolls *b b* and the second pair of rolls *c c* are originally set and Fig. 14 the 5 relative position to which they are adjusted after the series of bars or sheets have passed between the rolls in one direction, and the mill is reversed to pass them in the opposite direction between said rolls.

10 The shaft 31 is provided with a loose pulley 32, adapted to be connected to said shaft by a suitable clutch 80, so that the shaft may be turned in the opposite direction to run back the feed-screws after the rolling of the 15 series of bars or sheets or packs of sheets is finished or completed for the heat.

The rollers of the roller feed-table *d e f* are geared together by a series of gears 33 34 and by the bevel-gears 35 36, the gears 36 20 being on the shafts 37, which shafts are all driven from the shaft 38 by the pulleys 39 thereon, which are connected by chains with the pulleys 40 on said shafts 37. Motion is communicated to the shaft 38 from the shaft 25 *m* of the driven roll *b* by means of a bevel-gear 41 thereon, which meshes with a gear 42 on a shaft 43, which has a gear 44 meshing with a gear 45 on said shaft 38.

The movable side gages *l l* of the roller feed-table are automatically operated at intervals, 30 as required, by an arm 46, frictionally secured to the shaft *m* of the roll *b* and which is adapted to vibrate from one of the stops 47 47 to the other at each reversal of the rolls 35 and which is connected to the slides 48, carrying the opening and closing side gages *l l*, by means of links 49, pivoted to the friction cam or arm 46 and to a lever or arm 51, which is connected by a link 52 with a rack 59, that 40 meshes with a gear 60 on a rock-shaft 61, that is provided with a pair of lever-arms 62, connected by a link 63 and intermediate lever 64 with the gage-carrying slides 48 by a link 58, so that at each movement of the friction cam 45 or arm 46 the two gages *l l* are first made to momentarily close or approach each other to center and square the sheets on the feed-table and then at once to open or separate to permit the bars or sheets to be fed forward 50 into the bite of the rolls without again touching the gages, which might otherwise tend to disarrange the bars or sheets on the table before entering the rolls.

The bar feed or delivering devices *g g* are 55 rocked or oscillated by a hand - lever 65 through the connecting-rod 66, bent lever 67, connecting-rod 68, and rock-shaft 69, the two rock-shafts 69 being connected together by a link 70.

60 The series of stops *k* are operated by a foot-lever 71 through the connecting-rod 72, bent lever 73, connecting-rod 74, and rock-shaft 75, to which the stops or gates are connected.

The movable stops which are projected into 65 the path of the bar or bars being rolled serve to always accurately true the front edge of the bar, sheet, or pack parallel with the rolls,

so that the same will always properly enter the bite of the rolls. These stops thus in this combination with the rolls effectually prevents 70 the great difficulty and waste heretofore experienced and resulting from the bar, sheet, or pack entering the rolls slightly askew, thus causing the metal to elongate diagonally or draw to a point or "diamond-shaped," as it 75 is termed, a difficulty which if once started increases and aggravates itself rapidly at each successive pass of the metal between the rolls.

The feed-tables at each side of the mill and the conveyer between the rolls may be of any 80 suitable construction adapted to coöperate with the other parts. I have, however, for convenience illustrated in the drawings the well-known roller feed-table, as I prefer this feed to chain or other forms of feed-tables. 85

I claim—

1. In an automatic reversible rolling-mill, the combination of two stands of rolls arranged tandem or one in front of the other, each provided with a feed-table and connected by a conveyer between the two stands of rolls, with mechanism for reversing the two stands of rolls and driving both stands of rolls in unison first in one direction and then in the other, and means for adjusting both stands 95 of rolls in proper proportion, whereby the metal being rolled receives four passes or actions at each reversal, substantially as specified.

2. In an automatic reversible rolling-mill, 100 the combination of two stands of rolls arranged tandem or one in front of the other, each provided with a feed-table and connected by a conveyer between the two stands of rolls with mechanism for reversing the two 105 stands of rolls and driving both stands of rolls in unison first in one direction and then in the other, and mechanism for automatically reversing the two feed-tables and the connecting feed-table, and means for adjusting both 110 stands of rolls in proper proportion, whereby the metal being rolled receives four passes or actions at each reversal, substantially as specified.

3. The combination with the rolls and their 115 feed-table, of a bar feeding or delivering device above the feed-table for feeding or delivering a series of bars on the feed-table in line with each other one after another with a space between them to allow for their elongation in rolling, and mechanism for automatically reversing the rolls and feed-table, and laterally-movable side gages to center and true the bars or sheets on the feed-table, substantially as specified. 120

4. The combination with the rolls and their feed-table, of a bar feeding or delivering device above the feed-table for feeding or delivering a series of bars on the feed-table with a space between them to allow for their 130 elongation in rolling, and a series of movable gates or stops to regulate the distance between the bars, substantially as specified.

5. The combination with the rolls and their

feed-table, of a bar feeding or delivering device above the feed-table for feeding or delivering a series of bars on the feed-table with a space between them to allow for their elongation in rolling, a series of movable gates or stops to regulate the distance between the bars, and laterally-movable side gages for centering and truing the sheets on the feed-table, substantially as specified.

10 6. The combination with the rolls and their feed-table, of a bar feeding or delivering device above the feed-table for feeding or delivering a series of bars on the feed-table with a space between them to allow for their elongation in rolling, and laterally-movable side gages to center and true the bars or sheets on the feed-table and mechanism for automatically reversing the rolls and feed-table and mechanism for automatically operating said side gages, substantially as specified.

15 7. The combination with the rolls and their feed-tables, of bar feeding or delivering devices above the feed-table for spacing the bars upon the bed of the feed-table for the first pass between the rolls, and gages for squaring and truing the bars or sheets after the first pass, so that at each succeeding pass between the rolls the bars or sheets will be 20 delivered central and true to the bite of the rolls, substantially as specified.

25 8. In an automatic reversible rolling-mill, the combination with two stands of automatically-reversing rolls, of feed-tables adapted to deliver the bars or sheets to the bite of the rolls in each direction, and devices for gaging or squaring the metal bars or sheets upon the bed of the feed-tables between the passes, whereby the rolling of the bars or 30 sheets is caused to proceed rapidly, substantially as specified.

35 9. In an automatic reversible rolling-mill, the combination with two stands of reversing-rolls, of reversible feed-tables for conveying the heated bars or sheets to each of the stands of rolls in both directions, and mechanism for automatically setting down or adjusting the feed-screws of each of the stands of rolls in coöperative relation one to the 40 other to give the proper reduction to the metal at each pass of the bars or sheets between each stand of rolls, substantially as specified.

45 10. In an automatic reversible rolling-mill, the combination with two or more reversing stands of rolls and feed-tables, gears connecting the driven rolls of each stand, and a reversing device or mechanism adapted to take its power from a shaft revolving continuously in one direction and impart to each stand of rolls motion first in one direction and then in the opposite direction, and means for automatically adjusting both stands of rolls in proper proportion, substantially as 50 specified.

55 11. In an automatic reversible rolling-mill, the combination with two reversing stands of

rolls with feed-tables operating in unison therewith, with a reversing device, and mechanism for driving the rolls and feed-tables first in one direction and then in the other, and means for automatically adjusting both stands of rolls in proper proportion, substantially as specified.

60 12. In an automatic reversible rolling-mill, the combination with two reversing stands of rolls, of mechanism for driving and reversing the two stands of rolls in unison, feed-screws for setting the rolls of each stand closer together, and mechanism for automatically 65 turning the feed-screws at the reversal of the mill, substantially as specified.

65 13. In an automatic reversible rolling-mill, the combination with two reversing stands of rolls, of mechanism for driving and reversing the two stands of rolls in unison, feed-screws for setting the rolls of each stand closer together, and mechanism for automatically 70 turning the feed-screws at the reversal of the mill, said feed-screw-turning mechanism operating to turn the feed-screws of the second pair of rolls a greater extent than that of the first pair, substantially as specified.

75 14. The combination with two stands of rolls, of feed-tables furnished with laterally-movable side gages for centering and truing the bars or sheets on the feed-tables, a series of movable gates or stops for regulating the spacing of the bars, and mechanism for automatically operating said side gages, and mechanism for automatically operating said 80 movable gates or stops, substantially as specified.

85 15. The combination with two stands of rolls, of feed-tables furnished with laterally-movable side gages, a series of movable gates or stops for regulating the spacing of the bars or sheets on the feed-table, and a pair of bar feeding or delivering devices consisting each of a rocking or tilting box having slots or 90 openings on its opposite sides for delivering one bar when tilted to one side and another bar when tilted to the opposite side, substantially as specified.

95 16. The combination with the rolls and a feed-table, of a bar feeding or delivering device consisting of a rocking or tilting box having slots or openings in its opposite sides for the discharge of the bars as the box is tilted first to one side and then to the other, 100 substantially as specified.

105 17. The combination with the rolls and a feed-table, of two tilting boxes having slots for the discharge of the bars as the boxes are tilted, substantially as specified.

110 18. The combination with the rolls and a feed-table, of two tilting boxes having slots for the discharge of the bars as the boxes are tilted, and movable stops or gates to aid in spacing the bars on the feed-table, substantially as specified.

115 19. The combination with the rolls and feed-table of a rolling-mill, of a series of movable stops adapted to be projected into the path

of the bars or sheets on the feed-table to space them and true their front edges parallel with the rolls, so that they will properly enter the rolls at proper distances apart to allow for 5 their elongation in rolling, substantially as specified.

20. The combination with the rolls and feed-table of movable stops on both sides of the rolls adapted to project into the path of the

bar or sheet on the feed-table to true its front edge parallel with the rolls before entering the rolls in either direction, substantially as specified.

EDWIN NORTON.
